DESIGN FOR A KNEE REST

John A. RENCH, Lima, Ohio

Application October 6, 1936, Serial No. 65,180

Term of patent 14 years

To all whom it may concern:

Be it known that I, John A. RENCH, a citizen of the United States, residing in the city of Lima, in the county of Allen and State of Ohio, have invented a new, original, and ornamental Design for a Knee Rest, of which the following is a specification, reference being had to the accompanying drawing, forming part thereof.

The figure is a perspective view of a knee rest, showing my new design. The other side of the article is like the side shown.

I claim:

The ornamental design for a knee rest, as shown and described.

JOHN A. RENCH.
